Primary Examiner — Catherine S Posthauer(74) *Attorney, Agent, or Firm* — Winstead PC(57) **CLAIM**

We claim the ornamental design for a lid with a filter, as shown and described.

DESCRIPTION

FIG. 1 is a top perspective view of a lid with a filter showing our new design;

FIG. 2 is another top perspective view thereof;

FIG. 3 is a bottom perspective view thereof;

FIG. 4 is another bottom perspective view thereof;

FIG. 5 is a top view thereof;

FIG. 6 is a bottom view thereof;

FIG. 7 is a front view thereof;

FIG. 8 is a back view thereof; and,

FIG. 9 is a left view thereof.

The broken lines are shown for the purpose of illustrating parts of the article that form no part of the claimed design.
